Fig-3

FIGURE 1 is a front perspective view of a buffet or the like, showing my design wherein a single row of vertically stacked drawers is employed so as to convey an asymmetrical appearance;

FIGURE 4 is a front perspective view of the buffet of FIGURE 1 wherein two rows of vertically stacked drawers are employed so as to convey a symmetrical appearance;

The back of both embodiments of the buffet or the like is conventionally plain.

The dominant features of my design reside in those portions shown in full lines on the drawing.

I claim:

The ornamental design for a buffet or the like, as shown and described.
